UNITED STATES PATENT OFFICE.

WILLIAM H. SANBORN, OF ROCHESTER, NEW YORK, ASSIGNOR OF ONE-HALF TO WILLIAM H. STEVENS, OF PORTLAND, MAINE.

BRIDLE AND BRIDLE-BIT.

SPECIFICATION forming part of Letters Patent No. 352,506, dated November 9, 1886.

Application filed August 16, 1886. Serial No. 210,941. (No model.)

To all whom it may concern:

Be it known that I, WILLIAM H. SANBORN, a citizen of the United States, residing at Rochester, in the county of Monroe and State of New York, have invented certain new and useful Improvements in Apparatus for Controlling Horses; and I do hereby declare the following to be a full, clear, and exact description of the invention, such as will enable others skilled in the art to which it appertains to make and use the same.

My invention relates to means for controlling horses; and it consists in the application to a "four-ringed bit," so called, of a spheroidal-shaped button adapted to be pressed against the roof of the mouth by the lifting of the inner rings and the depressing of the driving-rings; and it further consists in the application to such a bit of a bridle-rigging adapted to force said button against the roof of the mouth, the said bridle being capable of being used as an ordinary driving-bridle.

My invention is illustrated by means of the accompanying drawings, in which Figure 1 shows my bit and bridle as applied to the horse. Fig. 2 is a view of the bit. Fig. 3 is a side view of the button. Fig. 4 is a view of an alternate form of bit to be used in special cases.

30 A represents a four-ring bit, a' a'' being the reining-rings, and a^2 the sliding rings. In the center of the bit is the spheroidal-shaped button a , which is linked or hinged to the two end sections of the bit. Although I prefer to use a button of spheroidal form, as here shown, yet the button can be made of any form, so long as it has a convex surface projecting upward toward the roof of the mouth when the bit is in position. This button may 40 be of wood, hard rubber, or other material which will be firm and capable of exerting a decided pressure against the roof of the mouth.

In operating my device the bit is placed in the horse's mouth. The driving-rein B is buckled to its ring in the usual manner. The two parts of the overdraw-check are buckled to the loose rings on each side of the mouth, and are then passed through the keeper or loop I , and thence through the rings O on the 50 crown-piece, terminating in the loops d , which are buckled to the overdraw at the required

point. The rein B passes through the loop d , this loop being adjusted on the overdraw, as will be hereinafter described.

The lower end of the keeper I has attached to it the thong or cord J , and it is held in its place by passing the ends of the cords through the rings J' , which are secured to the overdraw near the bit, and by tying the ends over the nose of the horse.

6c G is the throat-latch, and C is the cheek-strap, which is made double, and is adjusted by the single buckle c .

In using my apparatus for controlling vicious horses, I draw the keeper I down far enough to hold the bit loosely against the roof of the horse's mouth, and I secure it in position by the cord J . That portion of the overdraw which comes between the keeper and the bit will then be at or very nearly at right angles to the roof of the horse's mouth. The loop d is then buckled up to a considerable distance from the end of the overdraw. If, now, a pull is exerted on the rein B , the overdraw D will be drawn downward from the top 70 of the head, the draft being thence exerted through the keeper I to the ring a^2 . The ring a' is at the same time drawn downward and backward by the pull on the rein, so that the shank of the bit is formed into a lever, of 75 which the sliding ring a^2 forms the fulcrum, the central portion of the bit bearing the button a being forced upward against the roof of the mouth, and there pressing against the superior maxillary nerve. This pressure has an 80 instantaneous effect on the horse, controlling him and rendering him quiet and tractable. The force with which the button a is forced against the roof of the mouth is regulated by the keeper I being slid up or down on the nose 85 of the horse. The lower down it is placed the more nearly does the lower end of the overdraw come to being at right angles to the roof 90 of the mouth, and the more directly does the button press. The controlling action of the 95 bridle is also effected by the adjustment of the loop d on the overdraw D . When this loop is well up toward the top of the horse's head, a pull on the rein acts more directly on the overdraw than when it is near the end, as 100 shown in the drawings.

The bit may be used as a simple snaffle-bit

by fastening the driving-rein through both the rings a' and a^2 and withdrawing it from the loop d . In this case an addition is attached to the overdraw, extending it back to the water-hook in the usual way. When rigged in this manner, the pull on the rein simply draws the bit back into the horse's mouth.

In Fig. 4 I show another form of bit in which my pressure-button may be used. In this bit I use a chain, P , covered with a rubber envelope, R , so molded in the center as to form a button or projection eccentric with the shank of the bit, the amount of projection on one side being greater than on the other. The rubber which envelops the chain is sufficiently soft to impart considerable flexibility to the bit, and the projection or button is of sufficient firmness to exert the desired pressure on the roof of the mouth. The projection may be integral with the shank or attached to it. This flexible rubber bit, when applied to the horse's mouth, operates on precisely the same principle as that shown in Fig. 2; but it is much less harsh in its action, and is therefore adapted to horses having sensitive mouths. By constructing the central projection, R , eccentric with the shank I am able to regulate to a certain extent the amount of pressure produced. By turning the bit so that the longer or shorter projection shall come uppermost I produce greater or less pressure on the roof of the mouth.

My pressure-button may be applied to any four-ring bit having a joint in the center, or to a semi-flexible shank which will transmit

the pressure from the inner ring or fulcrum to the button.

It is evident that the form of the under side of the button is immaterial, as only the upper edge comes in contact with the roof of the mouth.

I am aware that bits have been made with driving-rings, and loose rings within said driving-rings, and central links jointed to the two parts of the shank; but such links were not adapted or designed to be pressed against the roof of the mouth.

I claim—

1. A flexible bit having an enlarged central portion of button shape or convex form projecting above the other portions of the bit, and provided with driving-rings and loose rings within said driving rings, substantially as shown. 50

2. The combination of a driving bridle, a flexible bit having a central enlargement or upward-projecting portion, driving-rings, and loose rings within said driving-rings, an overdraw-check attached to said loose rings, and provided at the ends with loops through which pass the driving reins, a loop or keeper through which the two parts of said overdraw-check pass, and means for holding said keeper in place, substantially as shown. 55

In testimony whereof I affix my signature in presence of two witnesses.

WILLIAM H. SANBORN.
